UNITED STATES PATENT OFFICE

2,319,629

SHREDDER BLADE

Theodore H. Poese, St. Louis, Mo., assignor to
 Gruendler Crusher & Pulverizer Co., St. Louis,
 Mo., a corporation of Missouri

Application May 25, 1942, Serial No. 444,349

1 Claim. (Cl. 83—11)

This invention relates to a certain new and useful improvement in blades especially, though not exclusively, adapted for use in shredding-machines and the like.

My invention has for its chief object the provision, as a new article of manufacture, of a shredding blade comprising a body-member uniquely equipped as a unit with divergently spaced sharp double-edge arms oppositely offset obliquely from the plane of the body-member for locating their sharp marginal edges for rotation in different rotary planes and the arms being so divergently angularly disposed one to the other as to present their sharp edges obliquely to the plane of rotation of the body-member for effective rapid shredding action upon the material subjected thereto, the blade being also conveniently reversible for prolonging its useful life.

And with the above and other objects in view, my invention resides in the novel features of form, construction, arrangement, and combination of parts presently described and pointed out in the claims.

In the accompanying drawing:

Figure 1 is a longitudinal vertical sectional view of a conventional shredding-machine equipped with blades constructed in accordance with and embodying my invention;

Figure 2 is an elevational view of a shredder-blade of my invention;

Figures 3 and 4 are edge and perspective views, respectively, of the blade; and

Figures 5, 6, and 7 are sectional views of the blade taken, respectively, on the lines 5—5, 6—6, and 7—7, Figure 2.

Referring now more in detail and by reference characters to the drawing, which illustrates a preferred embodiment of my invention, A designates a shredding-machine which, briefly for present purposes described, includes a shell or casing C having a hopper H and rotatable within which is a shredding unit comprising a shaft S, a series of spaced disks D fixed on the shaft S, an annular series of blade pivot-rods R fixed on the disks D in spaced parallel relation to the shaft S, and a grate or cage G through which the shredded material is discharged.

For effectively shredding the material fed into the hopper H, the shredding unit of the machine A also includes, in the present instance, a plurality of more or less rapidly revolving blades B of my invention loosely pivoted on the rods R.

Each blade B, which is constructed as a unit of suitable metallic material and generally of oblong-rectangular contour, as best seen in Fig-

ures 2 and 4, in turn, includes a body-portion b preferably rounded at its one or rear end, as at 1, is of suitable thickness for weight, strength, and rigidity, and is formed or provided adjacent its end 1 with an eye or aperture 2 for swingable mounting on a rod R.

The blade body-portion b is generally flat upon its opposite side faces, as at 3, 3, and is of a length to selectively extend suitably outwardly at its opposite or free end beyond the perimeter of the disk D for co-operation with the grate or cage G of the particular machine, the body-portion b of the blade B being longitudinally divided or bifurcated, as by a slot or cut-out 4 extending for a selected distance into the body-portion b from the outer or free end thereof to include what may be described as arms b¹, b².

At a selected line or location, as at 5, spaced somewhat rearwardly from the base of slot or cut-out 4, the metal of the blade B is upset or deformed so that the arms b¹, b², while generally extending longitudinally of the blade B, are oppositely and diverging or obliquely outwardly presented with respect to the plane of the body-portion b thereof, as shown.

Beginning preferably at a point, as at 6, disposed approximately midway of the body-portion b between the offset-line 5 and the rear end 1 thereof and extending to the outer end of the arms b¹, b², the blade B upon its opposite outer margins is chamfered or obliquely cut-away, as at 7, 7, and thereby formed or provided with correspondingly elongated sharp or cutting or shredding edges 8, 8.

Also beginning approximately at and along the offsetting line 5 and extending likewise to the outer end of the arms b¹, b², the blade B upon its opposite flat faces 3, 3, and along the inner side margins of the arms b¹, b², is further chamfered or cut-away, as at 9, and the arms b¹, b², thereby formed or provided along their inner side margins with sharp or cutting or shredding edges 10, 10.

So formed, each arm b¹, b², in cross-section, as on the line 7, 7, Figure 2, and as best seen in Figure 7, might well be described as having the shape or form of a rhomboid. However, as a result of the deformation of the metal of the blade B, the outwardly diverging relation of the arms b¹, b², and the marginal chamfering of the blade B as at 7 and 9, each blade B is provided or formed with two pairs of companion or co-operable cutting or shredding edges, that is to say, one pair comprising the outer cutting edge 8 of the one arm b¹ and the inner cutting edge

¹⁰ of the other arm b^2 and the other pair comprising the outer edge ⁸ of the one arm b^2 and the inner cutting edge ¹⁰ of the arm b^1 , the cutting edges of each such pair correspondingly extending in outwardly diverging oppositely disposed oblique relation.

Hence, on rotary actuation of the shredding unit of the machine A, the respective companion cutting edges ^{8, 10}, will be presented to the material being acted upon in divergently spaced planes obliquely angularly disposed to the plane of rotation of the body-member b of the respective blade B. The arms b^1, b^2 , thus effect what may well be described as a shearing cut upon such material and more or less rapidly tear and reduce such material to the desired degree of fineness for passing outwardly through the grate G, such reducing action being aided by the chamfered or oblique companion side faces ^{7, 9} of the blade.

It should be noted that, in the shredding unit of the machine A, the disks D are, of course, suitably spaced to accommodate the blades B and their diverging cutting arms b^1 and b^2 , and preferably the blades B pivotally hung upon a particular rod R are staggered with relation to the blades B pivoted upon adjacent rods R, so that the arms b^1 and b^2 of one set of blades B will traverse a zone correspondingly spaced from that traversed by adjacent blades, as will be well understood, for effecting the desired shredding action upon the material and efficiently increasing the output capacity of the particular machine. I might add that, by reason of the unique formation and structure of the respective blades B and their respective shearing and deflecting action upon the material being reduced, the resistance on the respective blades during rotation is reduced, lessening, in turn, the amount of required driving horse-power for the machine.

The blades B lend themselves to convenient sharpening of their cutting edges and, in addition, are conveniently reversible in the shredding unit of the machine for prolonging their useful life.

The blades B may be readily manufactured, conveniently installed in the particular machine, and are exceedingly efficient in the performance of their intended functions.

It should be understood that changes and modifications in the form, construction, arrangement, and combination of the several parts of the blade may be made and substituted for those herein shown and described without departing from the nature and principle of my invention.

Having thus described my invention, what I claim and desire to secure by Letters Patent is:

A reversible shredding-machine blade comprising a body-member generally of oblong-¹⁵ rectangular contour with approximately flat opposite side faces for the major portion of its area and longitudinally slotted for a selected distance from one end and thereby provided with a pair of arms, said arms being oppositely offset ²⁰ for divergently extending obliquely outwardly with respect to the main portion of the plane of the body-member, the body-member and one arm being continuously from a point disposed approximately midway of the body-member between its opposite end and the offset line of ²⁵ said arm obliquely chamfered along their outer side face and the body-member and the other arm being from said point oppositely obliquely chamfered also along their outer side face and the body-member and said arms being thereby provided with a pair of companion elongated outer marginal cutting edges extending in outwardly diverging oppositely disposed oblique relation to the body-member, said arms being oppositely chamfered obliquely upon their inner faces and thereby provided with inner marginal cutting edges also extending in diverging relation to the body-member and the edges of each of said pairs being disposed for rotation in different rotary planes, the chamfered inner and outer side faces of each respective arm being approximately parallel and each of said arms with their said chamfered inner and outer faces having the cross-sectional form of a rhomboid.

THEODORE H. POESE.
